CLAIM

The ornamental design for a hood vent for roll out cart, as shown and described.

DESCRIPTION

FIG. 1 is a perspective view of a hood vent for roll out cart showing our new design;

FIG. 2 is a front elevational view thereof;

FIG. 3 is a top plan view thereof;

FIG. 4 is a bottom plan view thereof; and,

FIG. 5 is a right side elevational view thereof, the left side being a mirror image of that shown.
